EJECTOR PUMP REFRIGERATING APPARATUS

Warren H. De Lancey, Springfield, Mass., assignor to Atlantic Development Company, Springfield, Mass., a corporation of Massachusetts

Application July 11, 1947, Serial No. 760,201

4 Claims. (CL. 62—4)

1

This invention relates to refrigeration apparatus of the so-called vacuum type, employing a centrifugal pump for the compression and circulation of the refrigerant fluid, a portion of the latter being circulated through an ejector or jet exhauster, for the entrainment of vaporized refrigerant drawn from the evaporator or cooling unit of the system.

The principal object of my invention is to simplify and lower the cost of such vacuum type refrigeration systems, and at the same time to improve the operation thereof. This is accomplished as hereinafter described, by the provision between condenser and evaporator, of a novel and highly effective valve mechanism for controlling the flow of the refrigerant to said evaporator.

With the above and other objects in view, as will hereinafter appear, the invention comprises the devices, combinations and arrangements of parts hereinafter set forth and illustrated in the accompanying drawings of a preferred embodiment of the invention, and the advantages attained thereby will be readily understood by those skilled in the art.

In the drawings:

Fig. 1 represents a diagrammatic view of refrigerating apparatus incorporating the present invention therein and showing certain of the elements in section.

Fig. 2 represents a vertical sectional view of the centrifugal pump of Fig. 1, taken substantially along the line 2—2 of Fig. 1, and showing also the thermostatic control of said pump's driving motor.

Fig. 3 represents, on an enlarged scale, a longitudinal sectional view showing the detailed construction of the control valve mechanism.

Fig. 4 represents an enlarged scale view of a portion of the valve unit disclosed in Fig. 3.

Fig. 5 represents an enlarged scale view of a portion of a check valve disclosed in Fig. 1.

Referring particularly to Fig. 1, the present invention is shown in association with a refrigerator which provides the usual cold box 10 having a door 11 removably secured over an opening 12 provided in said box. Disposed within the cold box 10 is an evaporator tank 13 the upper portion of which has connected thereto a low-pressure conduit 14. The lower end of the conduit 14 communicates with a substantially cylindrical housing 15 of an ejector unit 16 which is connected in series with a centrifugal pump contained within a pump housing 17.

Referring particularly to Figs. 1 and 2, the

2

above noted centrifugal pump comprises the usual rotatable impeller unit 18 which is mounted upon a shaft 19 journaled in the back wall of the housing 17. An electric motor 20 is coupled to the shaft 19 for the purpose of driving the impeller in the usual fashion. The centrifugal pump housing 17 is formed in the usual manner and is connected with an axial intake conduit 21 and a peripheral discharge conduit 22 which are adapted, respectively, to conduct the refrigerant fluid to the pump's axial intake and to discharge the same from the periphery of the pump under pressure. The centrifugal pump discharge conduit 22 extends from the pump housing 17 and into the ejector housing 15 which is hollow and thereby forms an ejector chamber 23. That portion of the conduit 22 which extends within the chamber 23 is provided with a nozzle portion 24 which is axially aligned with and spaced from the intake portion of the conduit 21 which also extends into the chamber 23. This intake portion of the conduit 21 is formed as an expanding passage or port 25 thereby to form, in conjunction with the nozzle 24 and the chamber, a jet exhauster or ejector. This serves, as is usual in vacuum type refrigerating systems, for the entrainment, via conduit 14, of refrigerant fluid that is vaporized in evaporator 13, through heat absorption from box 10, and by virtue of the lowered pressure resulting from such ejector action.

The so-circulated refrigerant, such as Freon 12, is supplied in proper quantities to the evaporator 13, after first passing through a suitable condenser 27, the latter being connected by a conduit 26 to the pump discharge conduit 22. From said condenser, a conduit 29 leads to the interior of a housing 33 (see Fig. 3) forming part of the special control valve mechanism, designated as a whole by the numeral 28, of my invention. Said valve mechanism, as hereinafter described in detail has a conduit connection 30 with the low-pressure line 14 of the system, and a conduit connection 31 with the evaporator 13, wherein the liquid refrigerant has a static level substantially as indicated by broken line 32, Fig. 1.

Referring particularly to Fig. 3, there is disclosed, on an enlarged scale, a longitudinal sectional view of the control valve mechanism 28. More specifically, said control valve mechanism is arranged in the substantially hollow cup shaped housing 33, the end portion of which is adapted to be closed over by means of an end cap 34. Bolts 35 (only one of which is shown

herein) secure the end cap 34 over the housing 33. Between the flange portions of the housing and the end cap 34 is clamped an external flange portion 36 of one end of a flexible metallic bellows 37. The other end portion of the bellows 37 has an internal flange portion which is brazed, or otherwise suitably secured, as at 38, to a hollow thimble member 39.

Formed in the wall portions of the housing 33, and communicating with the hollow interior thereof, are a pair of tapped apertures 40 and 41 the former receiving the conduit 29, and the latter receiving the conduit 31. Threaded into the inside portion of the aperture 41 is a stud element 42 which is provided with a longitudinal bore 43 communicating at one end directly with the aperture 41. The other end of the bore 43 is provided with a conical valve seat 44. Cooperating with the valve seat 44 is a conical needle valve element 45, one end portion of which is adapted to be carried by means of an annular plate 46 secured directly over the bottom portion of a cylindrical sleeve 47 which is adapted to surround one end of the stud 42. More specifically, the needle valve 45 is provided with a pair of spaced annular grooves 48 and 49, each of which is adapted to receive a snap ring 50. The disk 46 may be suitably brazed to the sleeve 47 and the needle valve 45 is held in position by having one of its snap rings 50 engage a face of the disk 46 and the other snap ring engage the face of a washer 51. Sandwiched between the washer 51 and the inner portion of the sleeve 47 is a soft rubber washer 52. It is the purpose of this rubber washer 52 to provide a resilient mounting in sleeve 47 for the needle valve so that the same will be self-aligning with the valve seat 44.

Between the closed inner end portion of the thimble 39 and the disk 46 is disposed a compression spring 53 which is adapted normally to bias the needle valve 45 towards the valve seat 44. From this, it will be understood that the needle valve 45 is normally urged towards the valve seat so that the bore 43 in the bellows position shown by Fig. 3 will be shut off from the interior portion of the housing 33. However, it is clear that when operation of the centrifugal pump causes the pressure of the refrigerant fluid to build up within the housing 33, it will be effective to bias the bellows 37 and their attached thimble 39 to the left, Fig. 3, which relieves the pressure of spring 53 on plate 46. At its outer end the thimble member 39 is formed with an internal groove 54 in which is mounted a washer 55 whose inner periphery is spaced from the peripheral portion of the sleeve 47 so as to permit free passage of fluids from opening 40 to opening 41 by way of apertures 91, 91 formed in the sleeve 47. It is the purpose of the washer 55 to engage the edge portion of the disk 46 whenever the bellows 37 has been compressed a distance equal to that designated by the letter Y. From this, it will be understood that a further movement to the left of the bellows 37 will be effective to unseat the needle valve 45 from the valve seat 44 thereby placing the bore 43 in communication with the interior portion of the housing 33 by way of the sleeve apertures 91, 91 and between the washer 55 and the sleeve 47.

Projecting into the interior portion of the housing 33 from the end cap 34 is a cylindrical extension 56. Threaded into one end of the end cap 34 is an adjusting screw 57, the right-hand end portion of which extends into a chamber 58

provided within the cylindrical member 56. Loosely mounted over one end of the adjusting screw 57 is a cap 59 against which one end of a pressure-regulating spring 60 is adapted to be biased. The other end of this spring 60 engages a second cap 61 which is normally biased against a snap ring 62 which is seated within an annular groove 63 formed about the inner periphery of the chamber 58. The reduced end portion of the thimble 39 is adapted to be biased into engagement with the cap 61 by means of the spring 53.

From the above, it is to be understood that the bellows 37 can be compressed a distance Y, against the action of the spring 60 without moving the needle valve 45, but that any further movement of the bellows against the spring 60 will be effective to shift the needle valve away from the valve seat 44.

Projecting from one face of the end cap 34 is a threaded boss 64 over which may be screwed an acorn nut 65. A gasket 66 may be placed between the nut 65 and a shouldered portion of the end cap thereby to prevent the escape of fluids from the chamber 58. Also, the nut 65 will be effective to protect the end portion of the adjusting screw 57 thereby to prevent the same from being inadvertently turned. By adjusting the screw 57 towards or away from the spring 60, the pressure of this latter element may be readily varied.

Formed in the end cap 34 is a tapped aperture 67 which communicates directly with the chamber 58. Referring particularly to Figs. 1 and 3, it is to be understood that the chamber 58 is placed in direct communication with the low-pressure conduit 14 by means of the connecting conduit 30 and that the condenser connection 29 is coupled directly to the aperture 40. Also, it is apparent that the aperture 41 communicates directly with the lower portion of the evaporator 13 by means of the interconnecting conduit 31.

From the above, it is to be understood that when the centrifugal pump is started up, the liquid refrigerant will completely fill the condenser 27 and thus enter the housing 33 and surround the exterior of the bellows 37 with the result that it will be effective to exert a pressure on these bellows tending to move the same in a left-hand direction. However, as hereinabove noted, the bellows 37 and the valve springs 53 and 60 are so designed that they will not permit the valve 45 to open until a predetermined pressure differential exists between the fluids contained within the condenser 27 and the evaporator 13. Nevertheless, as the centrifugal pump continues to run and build up the pressure of the liquid refrigerant, this pressure will soon become great enough to cause a sufficient pressure differential between the internal and external portions of the bellows 37 to shift the same toward the left until the washer 55 of the thimble member 39 bears against the disk 46. This initial movement of the bellows will increase the volumetric capacity of the high pressure side of the present apparatus. The corresponding decrease in the vacuum side of the apparatus is incidental but of no consequence. Of course, as soon as the pressure within the evaporator 13 becomes low enough to permit the boiling of the liquid, the heat within the chamber 10 will be absorbed by the vapors contained within the evaporator 13. Also, upon the lowering of the pressure within the low pressure side of the apparatus, it will be found that the pressure differential existing on either side

of the bellows 38 will be sufficient to continue to compress the spring 60 thereby to unseat the needle valve 45 and to place the evaporator 13 in direct communication with the condenser 27. Thus, the liquid refrigerant may pass from the condenser 27 and into the evaporator 13 to replenish the loss of refrigerant from the evaporator. From this, it will be apparent that the needle valve 45 will remain unseated from the valve seat 44 as long as the above noted pressure differential is maintained at a predetermined level. Also, whenever the pressure differential between the high and low pressure sides of the system drops, the needle valve 45 will first close, and thereafter a further pressure drop will cause the bellows to shift to the right thereby to decrease the volumetric capacity of the high pressure side of the system so as to force liquid up into the ejector unit 16 thereby to render the pumping system effective to restore the proper fluid pressure.

From the foregoing it will be noted that the control valve mechanism is effective to materially increase the volume of the high pressure side of the system before the valve 44 can open to permit the refrigerant to pass into the evaporator 13, this enabling the system to be operated without any necessity for providing a tank for the storage under pressure of the refrigerant. In this connection it is to be understood that the efficiency of a centrifugal pump depends upon the specific gravity of the fluid being pumped. Thus, such a pump functions well on liquids, but is very sensitive to gas. In other words, the presence of gas in the regenerative system of the present invention causes a sharp drop in the pressure.

In the operation of the here disclosed system, the ejector 16 will draw vaporized refrigerant in considerable quantities from the evaporator 13. Thus, during the continued operation of the centrifugal pump, there is always a tendency for it to draw in much more vapor than can be condensed before the pump inlet is reached, and under these conditions the pressure would drop sharply and the pumping action would slow down or practically cease. In the vacuum refrigerating systems of the prior art, this condition has necessitated the provision of large tanks for the accumulation and storage under pressure of the refrigerant, to permit the vaporized portions of same to separate from the liquid portions; without such tanks there would be no way to fill the regenerative system with liquid and thereby restore the pressure during the operation of the centrifugal pump. But in the vacuum system of my invention, the control valve mechanism 28, by its ability above described to increase the volume of the high pressure side of the system before the valve can be opened, enables such accumulator and separating tanks to be dispensed with. That is to say, in my improved system, whenever the pressure drops due to the fact that the pump is handling too much vapor, the discharge valve 44 throttles, so that liquid refrigerant is forced back into the ejector, after which the system again picks up pressure which causes the discharge valve to open, thereby to deliver refrigerant to the evaporator 13. It is to be understood, that when operating on liquid only, the centrifugal pump will generate a substantially higher pressure than needed to open the discharge valve, but as said pump begins to pump vapor, the pressure will drop to a point where the valve 44 opens up just enough to discharge

the refrigerant liquid into the evaporator 13 as fast as it condenses.

The present invention also contemplates the provision of a ball type (or other suitable type) check valve generally designated by the numeral 68. This check valve is disposed directly between the condenser and evaporator conduits 29 and 31 and comprises the usual valve ball 69 which is disposed within a valve case 70 so as to prevent the refrigerant fluid from by-passing around the valve 28 whenever the pump is operating. However, whenever the pump ceases to operate altogether, the ball 69 will drop in the usual manner thereby to permit the refrigerant fluid within the evaporator 13 to by-pass the valve 28 and run back into the condenser 27. Of course, this ball will not drop until the pressure differential between the high and low pressure sides of the system has dropped almost to zero and thus, this check valve does not alter the effectiveness or take the place of the bellows 37 which functions to increase and decrease the volumetric capacity of the high pressure side of the system in response to various changes in the pressure differential.

Referring particularly to Figs. 1 and 5, it is to be understood that the check valve ball 69 normally rests upon the open end portion of a pipe extension 88 which projects into the valve case 30 70. This extension 88 is provided about its peripheral portion with a plurality of openings or notches 89, 89 which permit the refrigerant fluid within the evaporator 13 and the conduit 31 to run back into the condenser 27 whenever the 35 pump ceases to operate. Of course, as hereinabove noted, whenever the pump is in operation, it will be effective to force the refrigerant through the condenser 27 and toward the evaporator 13. Such a movement of the refrigerant will 40 force the check valve ball 69 upwardly so that it will forcibly engage the valve seat 90 so as to prevent any fluid from passing through the valve case 70 and into the conduit 31.

Also provided with the refrigerating system of 45 my invention is a temperature control means which will be effective to deenergize the motor 20 whenever the temperature within the cold box 10 falls below a predetermined level. Furthermore, by the same token, this temperature control means will be effective to energize the motor whenever the temperature within the box rises above this predetermined level.

This temperature control means may take the 50 form of a thermostatic bulb 71 which may be placed in any appropriate portion of the cold chamber 10. This thermostatic bulb may contain a refrigerant vapor or a liquid and vapor and is connected to a bellows unit 72 by means of an appropriate connecting tube 71'. The bellows 60 72 is disposed within a control box 73 and has provided on one end thereof an upstanding pin 74 which engages the lower side of an arm 75 which is pivotally mounted about a pin 76. Engaging the upper side of the arm 75 is a rod 77 65 which is biased downwardly by means of a coil spring 78. The other end of the arm 75 engages one end of a switch arm 79 which is rockably mounted upon a pin 80. The other end of the arm 79 is provided with an electrical contact 81 70 which is normally spaced from a similar contact 81' carried by a normally stationary adjusting screw 82. From this it is to be understood that whenever the temperature rises within the cold box 10, the vapor within the bulb 71 will expand 75 thereby, in turn, to expand the bellows 72. As

soon as the bellows are expanded upwardly in opposition to the balancing spring 78, the arm 75 will be effective to snap the electrical contacts 81 and 81' together. By the same token, as soon as the temperature within the cold box 10 drops below a predetermined level, the fluids contained within the bulb 71 will contract with the result that the contacts 81 and 81' will be snapped apart by means of the balancing spring 78. The contacts 81 and 81' are effective to energize and deenergize the motor 20 for the reason that they are connected to one side of an electrical supply which is brought to the apparatus by means of wires 83. A throw switch 84 connects the electrical supply source with wires 85 and 86 of which the latter is connected directly to the motor 20. The other wire 85 is connected to the arm 79 and the contact 81' is connected with the motor by means of a wire 87. From this it will be understood that as soon as contacts 81 and 81' are in engagement, the motor 20 will be energized from the electrical supply source 83 and as soon as these contacts are opened, the motor will be immediately deenergized. Thus, this temperature control means will be effective to maintain the cold box 10 at a constant temperature at all times.

I claim:

1. In a refrigerating apparatus of the type described, an evaporator, a condenser, a centrifugal pump for forcing refrigerant through said condenser, an ejector connected in series with said centrifugal pump for drawing vapor from said evaporator, a normally closed connection between said condenser and said evaporator, a pressure-responsive valve which is adapted to open said connection in response to a predetermined pressure differential existing between the fluids contained within said evaporator and said condenser, and a pressure-responsive element for materially increasing the volumetric capacity of the high pressure side of said apparatus before said valve can open.

2. In a refrigerating apparatus of the type described, an evaporator, a condenser, a centrifugal pump for forcing refrigerant through said condenser, an ejector connected in series with said centrifugal pump for drawing vapor from said evaporator, a normally closed connection between said condenser and said evaporator, and means responsive to a predetermined pressure differential existing between the fluids contained within said evaporator and said condenser for increasing the volumetric capacity of the high pressure side of said apparatus before opening said connection between said condenser and said evaporator.

3. In a refrigerating apparatus of the type described, an evaporator of the flooded type, an ejector, a low pressure vapor-conducting conduit connecting said evaporator with said ejector so that the latter element will draw vapor from said evaporator whenever refrigerant is circulated through said ejector, pumping means for circulat-

ing refrigerant through said ejector, a condenser connected with said pumping means for receiving a portion of the circulating refrigerant, a high pressure refrigerant-conducting conduit connecting said evaporator with said condenser, refrigerant control means connected with both of said high and low pressure conduits, and means associated with said control means for regulating the flow of liquid refrigerant from said condenser to said evaporator in response to variations from a predetermined pressure differential existing between the fluids contained within the high and low pressure conduits thereby to maintain a substantially constant liquid refrigerant level within said flooded evaporator.

4. In a refrigerating apparatus of the type described, an evaporator, a condenser, a first refrigerant-conducting means, connecting said condenser with said evaporator and forming a part of the high pressure side of said apparatus, an ejector, a second refrigerant-conducting means forming a part of the low pressure side of said apparatus and connecting said evaporator with said ejector so that said ejector will draw vapor from said evaporator whenever refrigerant is circulated through said ejector, centrifugal pumping means, conduits connecting said ejector and said pumping means so as to form a substantially unobstructed and closed circulatory system, means connecting said condenser with one of said conduits, refrigerant control means connected with said first refrigerant-conducting means between said condenser and said evaporator, means connecting said control means with said second refrigerant-conducting means, means associated with said control means and responsive to various predetermined pressure differentials existing between the fluids contained within the high and low pressure sides of said apparatus for increasing and decreasing the volumetric capacity of the high pressure side of said apparatus, means responsive to predetermined variations in the pressure differential existing between said fluids for opening and closing said first refrigerant-conducting means, and a check valve connected between said evaporator and said condenser so as to by-pass said control means, said check valve being effective to place said evaporator and said condenser in direct communication with each other whenever the fluid pressure within the condenser drops below a predetermined quantity.
